(57) **CLAIM**

The ornamental design for tongs, as shown and described.

DESCRIPTION

FIG. 1 is a perspective view of tongs in accordance with the present design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines shown are included for the purpose of illustrating a portion of the tongs that forms no part of the claimed design.

1 Claim, 4 Drawing Sheets
